UNITED STATES PATENT OFFICE

168,035

CLOTHES SPRINKLER

Nan Jacobs, Topeka, Kans.

Application May 29, 1952, Serial No. 19,951

Term of patent 14 years

(Cl. D49—1)

To all whom it may concern:

Be it known that I, Nan Jacobs, a citizen of the United States, residing at Topeka, in the county of Shawnee and State of Kansas, have invented a new, original, and ornamental Design for a Clothes Sprinkler, of which the following is a specification, reference being had to the accompanying drawing, forming part thereof.

I claim:

The ornamental design for a clothes sprinkler, as shown.

NAN JACOBS.
